UNITED STATES PATENT OFFICE.

JOHN FERO, OF BELLINGHAM, WASHINGTON.

FIRE-LIGHTING DEVICE.

No. 924,752.

Specification of Letters Patent.

Patented June 15, 1909.

Application filed June 11, 1908. Serial No. 437,863.

To all whom it may concern:

Be it known that I, JOHN FERO, a citizen of the United States, and a resident of Bellingham, in the county of Whatcom and 5 State of Washington, have invented a new and Improved Fire-Lighting Device, of which the following is a full, clear, and exact description.

This invention relates to mechanical 10 means for lighting a fire in a stove or range at a predetermined time, and has for its object to provide novel details of construction for a fire lighter, which are simple, practical and inexpensive, and that afford a compact, 15 convenient device, which is controlled by the ordinary alarm mechanism of a portable alarm clock, and that will ignite fuel in the fire pot of a stove or range, when the alarm is put in motion at the instant of time for 20 which it was set.

The invention consists in the novel construction and combination of parts, as is hereinafter described and defined in the appended claims.

25 Reference is to be had to the accompanying drawings forming a part of this specification, in which similar characters of reference indicate corresponding parts in all the views.

Figure 1 is a side elevational view of the 30 complete device, partly broken away and in section; Fig. 2 is an end view of the device and a rear view of an alarm clock whereon the fire kindler is mounted; and Fig. 3 is a plan view of the device, and of a clock whereon said device is mounted, a portion of the clock case being removed and a part being in section.

The improved fire kindler, as before mentioned, is controlled in its operation by a 40 small alarm clock, of a class that is portable and is provided with a winged turn-button that affords means for winding up the alarm, said turn-button being mounted and secured upon the end of the shaft employed for winding the alarm, and which projects outside of the rear wall of the clock case as usual.

In the drawings, 5 indicates an alarm clock 45 of the character specified, which for convenience in placing the device adjacent to a stove or range, is mounted upon a standard 50 6 that is adjustably engaged with a tripod 7, as shown in Fig. 1, the standard being vertically adjustable on the tripod. Upon the side of the clock case that is circular, a 55 bracket shelf 5^a is mounted and secured, so

as to project laterally therefrom, as is clearly shown in Fig. 2.

The igniter mechanism comprises the following details: A preferably plate metal box 8, that is rectangular in contour for a portion of its length, has extended at one end thereof, a tapered arm 8^a, and at the extended end a match holder in the form of a bent limb *a* having a socket *b* on its free end, is secured, said limb being offset and bent at 60 an angle that will incline a match *c* therefrom, so that the head *c'* of the match carried in the socket *b* will be disposed in the path of an igniter plate to be hereinafter described.

70 A slot *d* is formed in the top wall of the box 8, and in said box a trigger bar *e* is pivoted at *e'* near its end *e*² that projects through the slot *d*; and as shown in Fig. 3, said end portion is roughened to afford a 75 thumb hold when the trigger is to be set, as will presently be described.

A coiled spring *g* is mounted upon the pivot *e'* at one side of the trigger bar *e*, and the ends of said spring are respectively engaged with the top wall of the box 8 near the slot *d*, and the trigger bar *e*, one end *g'* hooking upon the latter a distance below the pivot *e'*, and said spring is placed under tension so as to normally hold the trigger bar erect. 80 Upon the lower end of the trigger bar *e*, one end of a slide rod *h* is loosely secured, as indicated at *h'* in Fig. 1, and thence extends forwardly through the apertured front end of the arm 8^a and is integral with the igniter 85 plate *i* hereinbefore mentioned. The igniter plate *i* is roughened on the upper side thereof and is concaved somewhat on the upper side, so as to have positive contact with a match head *c'*, the body of the match *c* being carried by the socket *b* on the bent limb *a*.

Upon the top wall of the box 8, a rock arm 9 is pivoted near one end thereof, said end having a laterally projected hook *m* thereon, which may be hooked upon a shoulder *e*³ on 100 the trigger *e* near the upper extremity *e*² thereof, this engagement of the hook and shoulder being permitted only when the trigger *e* is rocked rearward at its upper end, as shown in Fig. 1.

105 A toe *m'* is extended laterally on the rear end of the rock arm 9, and when the rectangular box-like portion 8 of the match supporting arm 8^a is seated on the bracket shelf 5^a and is held in a horizontal position by the 110

clasping pressure of an upright flange *n* on said shelf, the toe *m'* will be projected through a notch *o* in the clock case and in the path of a wing on the winding turn-button 5 *p*, that affords means for winding the alarm mechanism and rotates in the direction of the curved arrow *x'* when said mechanism is released by the clock gear for sounding an alarm. A plate spring *r* presses the rock 10 arm and toe *m'* toward the turn button *p*.

In arranging the device for its service as a fire kindling means, assuming that a stove or range, not shown, has the necessary kindling placed in its firepot, and the clock alarm 15 mechanism has been wound and set at the exact time it is to sound an alarm, the clock and its supporting tripod are positioned near the range, so that the igniter plate *i* and match *c* are inserted into the firepot through 20 the grate bars of the latter, and into engagement with the kindling material therein.

It will be obvious that when the exact instant of time arrives for sounding an alarm, the action of the alarm mechanism will rotate the winged turn-button *p* which will strike upon the toe *m'* and rock the arm 9 so as to remove the hook *m* from an engagement with the shoulder *e'*, so that the spring *g* will forcibly rock the lower end of the arm 9 rearward and retract the slide rod *h*. The rod *h*, whereon the igniter plate *i* is carried and that has been projected forwardly when the trigger was set, is now, by the recoil of the spring *g*, forcibly retracted and the igniter plate *i* 35 drawn across the match head, which will ignite the match and kindle the fire in the stove or range simultaneously with the ringing of the alarm.

Having thus described my invention, I 40 claim as new and desire to secure by Letters Patent:

1. The combination with an alarm clock and a support thereon, of an arm carried on said support, a match carrier on an end of said arm, a trigger bar pivoted on the arm, a spring for moving the trigger bar, a slide rod actuated by the movement of the trigger bar and provided with means for igniting the match by frictional contact when the trigger 45 bar is released, and a pivoted and spring pressed rock arm adapted to engage the trigger bar to hold the same against the tension of its spring, the said rock arm being actuated by the alarm mechanism of the 50 clock to release the trigger bar.

2. The combination with an alarm clock having a winding turn-button on the alarm winding arbor, and a bracket shelf on the clock case, of a hollow arm seated on the shelf, a match carrier on the outer end of said arm, a spring pressed trigger bar pivoted on the arm, a rock arm having a hook on one end that engages with the upper end of the trigger bar, a slide rod pivoted by one end on 60 the lower end of the trigger bar, an igniter

plate on the outer end of said slide rod that may have contact with a match in the carrier, and a lateral toe on the rock arm that is engaged by the turn-button when the alarm is sounded.

3. In a device of the character described, the hollow arm, tapered toward one end and provided at said end with a match carrier, the trigger bar pivoted in the arm at its larger end, the upper end of said bar rocking 75 through a slot in the top wall of the arm, a coiled spring adapted for rocking the pivoted trigger bar upright, an igniting means for the match controlled by the movement of the trigger bar, a rock arm pivoted on the top 80 wall of the hollow arm near the upper end of the trigger bar, an alarm clock, a hook on one end of the rockable arm for engaging the trigger bar, and a toe on the other end thereof adapted to be engaged by a moving part of 85 the alarm clock to release the trigger bar.

4. In a device of the character described, the hollow arm having a rectangular box-like form at one end, and a tapered portion extended from said box formation, a bent arm 90 on the small end of the tapered portion having a socket at its free end adapted to receive a match, a trigger bar pivoted in the box-like formation and having a shoulder on its upper end that projects through a slot in the top 95 wall of the box formation, a coiled spring engaging the trigger bar and normally holding said bar upright, means controlled by the movement of the trigger bar for igniting the match, and a spring-pressed rock arm pivoted upon the top wall of the box-like formation, said arm having a lateral hook on one end that may engage the shoulder on the upper end of the trigger bar, and a toe on the 100 other end thereof adapted to be engaged by a moving part of the alarm clock to move the rock arm to release the trigger bar.

5. In a device of the character described, a hollow arm, a support for the same, a match carrier at the outer end of said arm, a trigger 110 bar pivoted on the arm, a spring for moving the trigger bar, a rock arm pivoted on the hollow arm and adapted to engage the trigger bar to hold the same against the tension of its spring, time-controlled mechanism for 115 moving the said rock arm to release the trigger bar, and a slide rod connected with the trigger bar, and provided with means for igniting the match when the trigger bar is released.

6. In a device of the character described, the combination with an alarm clock, an adjustable standard upon which said alarm clock is mounted, and a support on the side of the clock case and projecting laterally therefrom, of an arm carried by said support, a match carrier on the outer end of said arm, a trigger bar pivoted on the arm, a spring for moving the trigger bar, a rod connected with the trigger bar and provided with means for 125 130

igniting the match, and a pivoted rock arm for engaging the trigger bar, to hold the same against the tension of its spring, the said rock arm being actuated by the alarm mechanism 5 of the clock to release the trigger bar.

7. The combination with an alarm clock having a turn button on the alarm winding arbor, and a supporting shelf on the clock case, of mechanism carried by said shelf for 10 lighting a fire, the said mechanism comprising a rock arm having a hook at one end and a lateral toe at the other end, a spring pressing on said rock arm to hold the toe in the path of said turn button, a pivoted trigger

bar, a spring for normally holding said trigger 15 bar erect, the said trigger bar having a shoulder adapted to be engaged by the hook on said rock arm to hold the trigger bar against the tension of its spring, a match carrier, and means actuated by the movement of the 20 trigger bar for igniting the match.

In testimony whereof I have signed my name to this specification in the presence of two subscribing witnesses.

JOHN FERO.
